UNITED STATES PATENT OFFICE.

RAPHAEL VON OSTREJKO, OF CRAKOW, AUSTRIA, ASSIGNOR, BY MESNE ASSIGNMENTS, TO THE CHEMICAL FOUNDATION, INC., A CORPORATION OF DELAWARE.

PROCESS OF PRODUCING DECOLORIZING CHARCOAL.

1,362,064.

Specification of Letters Patent.

Patented Dec. 14, 1920.

Application filed December 13, 1916. Serial No. 136,701.

To all whom it may concern:

Be it known that I, RAPHAEL VON OSTREJKO, a native of Kovno, chemical engineer, a subject of the Emperor of Russia, and resident of Crakow, Austria, have invented certain new and useful Improvements in Processes of Producing Decolorizing Charcoal, of which the following is a specification.

10 The previous methods of producing decolorizing charcoal, consist in subjecting the charcoal while in a state of red heat, to the action of superheated steam. My invention relates to an improvement in the 15 methods, heretofore used, which, in addition to a saving in fuel affords a highly active product suitable for the decolorization and deodorization of liquids, and for electro-technical purposes.

20 In accordance with my invention, the combustible gases, which are formed by the interaction of the superheated steam and the red hot charcoal, are burned, together with a suitable addition of air, in the furnace employed for heating the retorts; the result being that, as soon as a certain temperature has been attained, all further supply of fuel may be entirely stopped. When the decolorizing charcoal is ready, a portion thereof is emptied into vessels placed underneath the retorts, and thence conveyed, through conduits arranged in the plant, to the rear of the furnace. The charcoal is then subjected for a time, to the action of a considerable degree of heat, while entirely excluding the admission of air, in order to permit the charcoal to attain the properties desired to the highest degree possible. In the place of the charcoal withdrawn, the retort is fed 35 with a fresh supply, so that the plant may be kept in uninterrupted operation.

The plant serving to practically carry out my present improved process, essentially comprises a furnace, having an ash-pit; a 45 chamber in which the vertical retorts are bricked in, and a chamber for the steam superheater. The flue-gases, according to the arrangement, first come into contact with the retorts, then passing over the superheater tubes, and, finally, pass off through the chimney. My invention embodies a special manner of bricking in the retorts; further, a particular form of construction of the bottom 50 portions of the retorts; also, the arrangement of special passages for the supply of air for

combustion of the gases withdrawn from the retorts, and, lastly, a particular form of construction of the steam superheater.

One form of construction of the plant, according to my invention, is illustrated, by 60 way of example, in the accompanying drawings, in which Figures 1 and 1^a together show a complete vertical longitudinal section, Fig. 1 representing the upper half of the plant, and Fig. 1^a the lower half; Fig. 65 2 is a vertical cross section; and Fig. 3 is a horizontal section of the same.

The plant comprises an oven *a* within which four vertical retorts *b*, of a refractory material, are bricked in. Each of the said 70 retorts *b* is provided at its upper tapered end with a tubular projection or neck *c* carrying a lid *d*, and into which projection a supply pipe *e* terminates, through which superheated steam may be supplied from a 75 steam superheater *f*.

The oven *a* is provided with a furnace *g*, having a door *h* and a grate *i* of fireproof bricks, and it communicates with an ash-pit *j*. Communication between the furnace 80 and the ash-pit is established not only by the grate-openings, but also by means of special conduits *k*, *l*, the purpose and manner of operation of which will be dealt with hereinafter.

The flue-gases pass from the furnace through the openings in the pierced, fireproof wall *g'*, into the space between the fireproof jackets *b'* of the retorts *b*, which are held apart by fireproof bricks *b²*. (Cf. 85 Fig. 2.)

In the upper portion of the oven, the space above the jackets proper *b'*, and between the retorts *b* and the inner fireproof lining of the oven, is filled in with fireproof 95 bricks *b³*, disposed checker boardwise, in such a manner as to give rise to the formation of zigzag shaped passages. The result of this arrangement is that in consequence of the coöperation of the open-work 100 wall *g'* and the bricks *b³*, the flue gases distribute themselves uniformly and take an extremely sinuous path through the inner space of the oven. By this arrangement, the flue-gases are completely utilized. 105

The interior of the oven communicates with the space *n* wherein the superheater pipes *f* are disposed by means of an exhaust flue *m*, (Fig. 1), so that the flue gases necessarily pass through the space *n* in 110

order to reach the flue o (Fig. 1^a) of the chimney. In addition, the interior of the furnace g is in communication with the interior of each retort b in the following 5 manner: The tapered lower portions of the retorts b , which are provided with openings p close to their edge, and are adapted to be closed by perforated slide plates q of a refractory material, terminate in spaces or 10 conduits r , each of which communicates, by means of two conduits r' , facing one another, with the collector channel s arranged to terminate at s' in the furnace. The conduits r are fairly wide; they are accessible 15 from without and may be closed by doors r^2 . The steam supplied by a suitable generator initially flows through the U-shaped tube u , which surrounds the superheater pipes proper f and which is provided at the 20 bottom with a tube t carrying a valve t' and serving for the delivery of the water of condensation. From the tube u , in which the steam is dried and preheated, the steam passes through the connection tubes 25 u' and u^2 , to the horizontal tube u^3 , and thence through the valve f' into the four superheater tubes proper f , which are heated by the fuel gases passing through the vertical space or flue n ; each of the tubes f 30 being in communication by means of a tube e with the interior of a retort b .

The furnace g is furthermore provided with side openings g^2 , adapted to be closed when required, and the purpose of which 35 will be explained later on when the mode of operation of the plant is dealt with. The ash-pit j is accessible from without by means of a door j' and is provided with an opening v formed in the side wall, the area 40 of which may be adjusted as desired.

The plant is moreover provided at suitable places with inspection holes w , w' , for 45 observation of the temperature to be observed, and they may be closed by stoppers made of burnt fire clay.

The whole plant is reinforced in the longitudinal as well as in the transverse direction by means of rods y , provided with stretching straps x .

50 The manner of operation of the plant is as follows:

The lids d of the retorts b being removed, the retorts are charged from above with charcoal in a comminuted state. After 55 that, the lids are hermetically closed and a fire is started on the grate i , all the slides and steam valves being closed. The fuel-gases flow in the manner previously set forth through the furnace, and, after having heated the retorts from without, pass 60 through the discharge tube m and the superheater space n , to the flue o of the chimney. As soon as the retorts have been heated up to a red heat, (a fact which may be determined by peeping through the openings w)

superheated steam is admitted into the retorts by opening the valves f' . The steam acts chemically on the charcoal and liberates combustible gases which pass through the openings p and the holes in the slide plates q into the conduits r underneath the retorts thence to be drawn into the furnace through the conduits r , r' and s , s' , where they are finally burned.

As soon as the front end of the oven has 75 become white hot, the amount of steam supplied to the retorts is increased and, at the same time, the fire-door h and the door j' of the ash-pit j , are hermetically closed. In consequence of this arrangement, the admission of air to the furnace is possible only 80 by way of the adjustable opening v and the conduits k , l , adjustable by means of the slides k' . The subsequent heating of the plant is effected without the addition of 85 fresh supplies of fuel, and in such a manner, that the combustible gases, which have been formed by the action of the steam on the charcoal in the retorts, and which pass into the furnace through the conduits r , r' and s , s' are burned in the furnace in the presence of air admitted through the openings v , k and l . The waste gases serve 90 to heat the furnace and the retorts; so that, speaking in a certain manner, the entire operation is carried through in a cycle.

As soon as a portion of the decolorizing charcoal is ready, a certain quantity thereof is discharged into suitable vessels arranged in the conduits r , by opening the perforated slides q which are provided with operating-rods q' ; after which the charcoal thus withdrawn is conveyed through the openings r^2 .

At this stage the charcoal possesses to a 105 certain extent, though not yet fully, the particular properties desired. In order to still further improve the charcoal, it is conveyed through the side openings g^2 , which are adapted to be closed, to the rear portion 110 of the furnace g , which is heated to a white heat. The admission of air from the atmosphere into the furnace is entirely excluded for a time, by closing the slide k' and the door v .

115 It will thus become obvious that the partially prepared decolorizing charcoal is contained exclusively within the furnace in an atmosphere of hot combustible gases mounting from the retorts, and that the charcoal 120 is heated in the furnace until it becomes white hot. The charcoal has now been thoroughly treated and may be removed from the furnace. The charcoal withdrawn from the retorts is replaced by untreated charcoal 125 which is charged into the retorts from above, as hereinbefore described.

What I claim is:

The herein-described process of producing decolorizing charcoal, which consists in ex- 130

teriorly heating the retorts containing the charcoal to a red heat by means of a furnace; thereafter admitting superheated steam to the heated charcoal in the retorts, 5 to liberate combustible gases by the chemical action of the steam on the charcoal; leading said combustible gases from the lower portion of the retorts to the furnace for ultimate consumption therein, so as to there-
10 after heat said retorts solely by said gases; discharging a portion of the partially-pre-

pared charcoal from the retorts into the furnace; and finally completing calcination of the charcoal in said furnace while totally excluding air.

Signed by me at Vienna, Austria, this 24th day of October, 1916.

15

RAPHAEL VON OSTREJKO.
